Primary Examiner — W. A. Teddy Falloway

CLAIM

The ornamental design for a container for cosmetic products as shown and described.

DESCRIPTION

FIG. 1.1 is a front elevation view of a container for cosmetic products showing my new design;

FIG. 1.2 is a back view thereof;

FIG. 1.3 is a perspective view thereof;

FIG. 1.4 is an exploded view of the design in FIG. 1.1;

FIG. 1.5 is an exploded view of the design in FIG. 1.2;

FIG. 1.6 is another perspective view of the design in FIG. 1.1; and

FIG. 1.7 is a perspective view of the cap component of the container for cosmetic products, shown separately for clarity of disclosure.

In the design, the cap portion of the container for cosmetic products is excluded from protection.

1 Claim, 7 Drawing Sheets
